UNITED STATES PATENT OFFICE.

CHARLES I. MATSON, OF CHICAGO, ILLINOIS.

SAFETY-RAZOR MOTOR AND THE LIKE.

1,405,794.

Specification of Letters Patent.

Patented Feb. 7, 1922.

Application filed August 14, 1920. Serial No. 403,522.

To all whom it may concern:

Be it known that I, CHARLES I. MATSON, a citizen of the United States, residing at Chicago, county of Cook, and State of Illinois, 5 have invented certain new and useful Improvements in Safety-Razor Motors and the like, of which the following is a specification.

The present invention has to do with improvements in momentum motors intended for performing a certain class of work; and more particularly relates to certain improvements in momentum motors used for the operation of an improved type of safety 15 razor.

The momentum motor of the present invention is especially intended for the operation of safety razors of the general type shown in Letters Patent of the United 20 States No. 1,210,340, which was issued to me December 26, 1916. In the construction disclosed in the said Letters Patent, there is provided a relatively small slotted tube having the edges of its slit sharpened, with 25 which tube there co-operates a rotatable blade member having sharpened edges which co-operate with the edges of the slit to perform the cutting function by a shearing action. These two members are to be 30 rotated relatively with respect to each other at a comparatively high speed, and the momentum motor of the present invention is intended to perform this class of work in particular.

In the use of the type of safety razor above referred to the tubular member is placed against the surface of the skin with the slit close to the surface and as the hairs enter the slit they are sheared off. In order 35 to use this device to best advantage, it is essential that it should be so shaped that it can be readily and conveniently moved about over the skin of the user; and should therefore be provided with a handle or grip 40 of convenient form for this purpose. One of the objects of the present invention is to provide a handle or grip of such form that it can be very conveniently held and manipulated; which handle or grip also serves 45 as a convenient member within which to place the operating parts of the momentum motor.

Another feature of the invention has reference to the provision of an arrangement 50 whereby the fly-wheel of the momentum motor may be readily brought up to a high

speed of rotation by the use of suitable gearing, which gearing is then disengaged so that during the shaving operation the motor will run very smoothly and without 60 added vibration which would ordinarily be occasioned by the operation of gears during the shaving operation. This disengagement of the gears during the shaving operation will also reduce the friction so that the machine will continue to operate for a much longer time than would otherwise be the case. 65

Other objects and uses of the invention will appear from a detailed description of 70 the same which consists in the features of construction and combinations of parts hereinafter described and claimed.

In the drawings:

Figure 1 shows a longitudinal section 75 through the momentum motor of the present invention showing the same in its operative attachment to the safety razor itself;

Fig. 2 shows a section taken on the line 2-2 of Fig. 1 looking in the direction of the 80 arrows;

Fig. 3 shows a section taken on the line 3-3 of Fig. 1 looking in the direction of the arrows;

Fig. 4 shows a longitudinal detailed section 85 through the safety razor element; and

Fig. 5 shows an enlarged detailed section through certain of the operating gears of the momentum motor.

The safety razor itself is designated in its 90 entirety by the numeral 6. It includes a tubular member 7 having a longitudinally extending slit 8, the edges 9 and 10 of which slit are sharpened; and an interior rotary element 11 having a series of transverse slits 95 12 whose edges are sharpened and co-operate with the edges 9 and 10 in the cutting function. This type of construction is well illustrated and set forth in the aforesaid Letters Patent of the United States No. 100 1,210,340, and I will therefore not burden this specification with a more detailed description of the same.

The momentum motor is designated in its 105 entirety by the numeral 13. It comprises a cylindrical casing 14 having a central transverse partition 15 dividing it into two chambers. A fly-wheel 16 occupies one chamber and suitable gears presently to be described in detail, occupy the other chamber. End 110 walls or caps 17 and 18 are provided for closing the two chambers aforesaid.

The fly-wheel 16 is provided with end bearings working in the partition 15 and end wall 17. One of these bearings 18 is connected to a flexible shaft 19 which shaft 5 passes through a tubular member 20 and is connected to the rotary cutting element 11. The inner end 21 of the tubular support 20 is removably fastened to the end wall 17; and the outer end of the tubular member 20 10 is removably fastened to the stationary tubular member 7 of the razor. This latter attachment may be by means of a thumb screw 22 working into a suitable socket in member 7.

15 It is observed in Fig. 1 that the tubular member 20 is bent near its outer end so that the safety razor elements lie at an angle to the axis of the fly-wheel shaft. It is also observed in this connection that the slit 8 of 20 the safety razor lies substantially in the plane within which the tubular support 20 lies, so that when the slit 8 is presented directly to the face of the user, the momentum motor itself is held away from the face a 25 distance depending upon the angle of bend of the tubular support 20 and the length of said support. This makes it very much easier and more convenient to operate the razor; and at the same time makes it possible 30 for the user to accommodate the momentum motor in the palm of his hand while grasping the tubular support 20 with his fingers during the shaving operation.

Considering the construction of the momentum motor itself more in detail, the inner bearing of the fly-wheel 16 extends 35 through the partition 15 and carries a pinion 23. A shaft 24 having an operating crank 25 is journaled in the partition 15 and 40 in the end wall 18^a, and said shaft 24 is permitted a certain amount of endwise movement. The fly-wheel 16 has a circular recess 26 for the accommodation of the inner end 27 of the shaft 24 so that said shaft can be 45 moved endwise through the prescribed distance without interfering with the fly-wheel.

A gear 28 is secured to the shaft 24 as shown in Fig. 5. Meshing with said gear is 50 a pinion 29 journaled on a pin 30 which pin extends between the partition 15 and the end wall 18^a; the pinion 29 is integral with a gear 31 which reaches back adjacent to the inner surface of the gear 28 as shown in Fig. 5. A pinion 32 and gear 33 are integrally 55 formed and are journaled on the shaft 24 so that they are free to rotate thereon. Said pinion 32 meshes with the gear 31; and the outer face of the gear 33 lies adjacent to the inner face of the gear 31 as is clearly shown 60 in Fig. 5. A spring 34 secured to the partition 15 presses against the inner face of the gear 33 and tends to move said gear away from said partition; and such movement will necessarily carry with it all of the other 65 gears of the train. When the handle is

pushed inwardly, the gears are moved against the tendency of such spring and the gear 33 is brought into mesh with the pinion 23 during operation of speeding up the fly-wheel. As soon as the handle is released, 70 the gears automatically disengage leaving the fly-wheel free to rotate without interference.

Reference to Fig. 1 will disclose the presence of a slip coupling 35 between the fly-wheel 16 and the flexible shaft 19. This slip coupling will permit the parts to slip, if necessary, in case the rotary element of the 75 razor should become jammed.

I claim:

1. A momentum motor for the purpose specified comprising in combination a cylindrical member, a central partition dividing the interior thereof into two cylindrical chambers, a fly wheel journaled within one 85 chamber and having its shaft projecting through the partition into the other chamber, a pinion on the projecting end of said shaft, a driving extension on the other end of said shaft, there being an annular recess in that side of the fly wheel adjacent the partition, a crank shaft journaled in the partition and the other end of the cylindrical member, said crank shaft being free to move axially of its length, and the inner 90 end of the crank shaft being accommodated within the recess of the fly wheel, a main gear secured to the crank shaft adjacent the end wall of the chamber, a pinion and gear 95 rotatably mounted on the crank shaft adjacent the said main gear, a spring secured to the partition and working against the pinion and gear aforesaid and tending to move the crank shaft outwardly, and another pinion and gear working in conjunction 100 with the first mentioned gear and the pinion aforesaid, for the purpose of multiplying speed of the pinion and gear, whereby when the crank shaft is forced inwardly 105 against the pressure of the spring the gear 110 of the pinion and gear is caused to mesh with the pinion of the fly wheel, and whereby when pressure on the crank shaft is released all of the gearing is disengaged from the fly wheel pinion, substantially as described.

2. A momentum motor for the purpose specified comprising in combination a cylindrical chamber, a fly wheel journaled in one end thereof, a pinion secured to the fly 115 wheel, a longitudinally movable crank shaft journaled adjacent the inner face of the fly wheel, there being a circular recess for the accommodation of the inner end of said crank shaft, a gear secured to the crank 120 shaft, a pinion and gear rotatably mounted on the crank shaft adjacent said gear, a spring working in conjunction with said parts tending to move the crank shaft and gear 125 and pinion and gear away from the fly 130

- wheel pinion, and means for transmitting motion from the crank shaft gear to the pinion of the pinion and gear, whereby when the crank shaft is forced inwardly 5 against the spring the gear of the pinion and gear is engaged with the fly wheel pinion, and whereby when the crank shaft is released said parts are disengaged, substantially as described.
- 10 3. A momentum motor for the purpose specified comprising in combination a fly wheel, a pinion thereon, a longitudinally movable crank shaft, a gear thereon, a spring working against said gear tending to move said gear and crank shaft away 15 from the fly wheel pinion, and means for driving the gear by the use of the crank shaft, whereby when the crank shaft is forced against the spring said gear is engaged with the fly wheel pinion, and where- 20 by when the crank shaft is released the gear is disengaged from the fly wheel pinion, by the spring substantially as described.

CHARLES I. MATSON.
